FISHING LINE CLIP

Herbert J. Mayer, 1153 Chevy Chase Drive,
Anaheim, Calif. 92805

Filed June 18, 1970, Ser. No. 23,551

Term of patent 14 years

Int. Cl. D22—05

U.S. Cl. D22—25

FIG. 1 is an isometric view showing the top, one end, and one side of my new fishing line clip design;

FIG. 2 is an isometric view showing the bottom, other end and other side of my new design;

FIG. 3 is a top view of the clip;

FIG. 4 is a side view of my new design;

FIG. 5 is a bottom view of my new design;

FIG. 6 is a view of one end of my new clip; and,

FIG. 7 is a view of the other end of my new clip.

I claim:

The ornamental design for a fishing line clip, as shown.
